UNITED STATES PATENT OFFICE.

CHARLES E. WIRTH, OF WATERBURY, CONNECTICUT, ASSIGNOR TO THE PLUME & ATWOOD MANUFACTURING COMPANY, OF WATERBURY, CONNECTICUT, A CORPORATION OF CONNECTICUT.

MATCH-BOX HOLDER.

976,533.

Specification of Letters Patent. Patented Nov. 22, 1910.

Application filed July 9, 1910. Serial No. 571,125.

To all whom it may concern:

Be it known that I, CHARLES E. WIRTH, a citizen of the United States, residing at Waterbury, in the county of New Haven 5 and State of Connecticut, have invented an Improvement in Match-Box Holders, of which the following is a specification.

My invention relates to a match box holder made of sheet metal spun up from one piece,—a holder adapted to be set upon a table or mantel, or other support of fixed character.

My invention relates to improvements in the same in regard to the manner of holding 15 the match box.

Various articles for this purpose have heretofore been devised, each with its individuality of construction, and the device of my invention is an improvement upon the 20 same.

In carrying out my invention, I make the tray with a central rising conical member spun up complete from a sheet metal blank. The rising conical member is at the center 25 of the tray and I cut this member across by parallel spaced grooves and then across at right angles to divide the center into two arms which are bent into upright positions with the ends turned toward one another.

The outer shell or cover of the match box fits over the arms and into the grooves between the same and the parts of the conical member, which latter come outside of the shell or cover.

The match tray is passed inside of the shell and rests in an upright position upon the in-turned ends of the arms where the matches are accessible.

In the drawing, Figure 1 is a plan of the 40 match box holder of my invention. Fig. 2 is a cross section of the same at about the dotted line x, x , of Fig. 1. Fig. 3 is a cross section at right angles to the cross section of Fig. 2, and at about the dotted line y, y , of Fig. 1, showing the central portion of the holder, and Fig. 4 is a plan at about the 45 central portion of the holder showing the condition of the central portion prior to turning up and finishing the construction 50 of the arms. In Fig. 2 I have also shown the match box in position.

a represents the tray of my improved match box holder formed from a sheet metal blank spun up to shape as a unit or integral

structure and having at the center a rising 55 conical member b . This conical member is cut across to form the channels 2 3 by a suitable tool, and the central portion of the intervening metal is cut across at right angles and at the center by the line shown in 60 Fig. 4. Thus two arms $c c^1$ are formed. These are then up-turned as shown in the other figures of the drawing and similarly and preferably are each provided with a groove 4 to stiffen and strengthen the arms 65 in their upright position, and the free ends of these arms are then appreciably over-turned.

d represents the shell or cover of the match box; d^1 the match holding tray.

In Fig. 2 the position of the shell or cover d is illustrated in which the ends are passed over the arms $c c^1$ and the sides are passed between the edges of the arms and the upright faces of the rising conical member b 75 which has been cut across to form the arms so that the ends of the shell or cover fit down over the arms and within the parts of the rising conical member and the bottom of the channels or grooves 2 3.

The match holding tray d^1 is placed within the shell or cover d and rests upon the over-turned ends of the arms as illustrated in Fig. 2, and is so supported for use; the matches being accessible because about one-half of the length thereof are exposed above the upper end of the shell or cover d .

The match box holder of my invention is exceedingly simple and inexpensive to make and as the same is a unitary or integral 90 piece of metal the expense of manufacturing is reduced to a minimum.

I claim as my invention:

1. A match box holder comprising a tray, a central rising conical member spun up 95 from one piece of sheet metal, arms formed from the conical member by cutting out portions of the metal to form parallel channels across the same equally spaced apart, and the center divided across and said arms 100 turned up into an upright position with their free ends turned over.

2. A match box holder comprising a tray, a central rising conical member spun up 105 from one piece of sheet metal, arms formed from the conical member by cutting out portions of the metal to form parallel channels across the same equally spaced apart, and

the center divided across and said arms turned up into an upright position with their free ends turned over, and vertical grooves placed about the center of said arms 5 for stiffening and strengthening the same.

3. A match box holder comprising a concave tray and rising convex central portions, spaced apart arms formed integral with the tray and from the central portion and bent 10 into an upright position, with the free ends

overturned and the edges of the arms separated from the edges of the rising central portion a distance sufficient to receive between them the shell or cover of a match box in an upright position.

Signed by me this 30th day of June 1910.
CHAS. E. WIRTH.
